UNITED STATES PATENT OFFICE

1,967,358

NONREFILLABLE LIQUID DISPENSER

Vivian J. Gianelloni, Central San German, Cuba

Application February 9, 1934, Serial No. 710,463

2 Claims. (Cl. 220—86)

This invention relates to non-refillable containers, and particularly to a non-refillable liquid dispenser.

One object of the invention is to provide a dispensing tank with a pump-tube secured therein and provided with a check-valve and with a guard to prevent access to the valve and with an instrument that is operable to hold the valve open while re-filling the tank.

Another object is to provide an improved form of pump-tube that is particularly useful in combination with a tank which has a sheet-metal head and sheet-metal bottom, and to provide improved connections of the pump-tube with the said head and bottom in proper relation to provide a rigid connection of the pump with the comparatively flexible sheet-metal of which the tank is composed.

Another object is to provide, in the head of the tank, an air-vented pump-connection through which the pump-tube extends in normally secure and sealed relation and also in such adjustable relation that the air-vents can be opened and closed thereby, so as to permit air to enter while liquid is being dispensed, and to prevent leakage and evaporation when the device is not in operation.

Another object is to provide the pump-tube with air-holes that are normally closed by the valve-guard and adapted to be opened in the event the valve-guard is moved from its seat, thereby rendering the pump inoperative for those who would tamper therewith for refilling the tank.

Other objects and important features are pointed out or implied in the following details of description, in connection with the accompanying drawing in which:

Fig. 1 is a view showing the tank in vertical section, and the pump in its operative relation in side elevation.

Fig. 2 is an enlarged detail view, in vertical section, showing fragments of the upper and lower walls, or head and bottom, of the tank, the vented pump-connection having the upper end of the pump-tube secured and sealed therein, and the lower end of the pump-tube seated in its detaining depression, the middle of the pump-tube being broken out.

Fig. 3 is a top plan view of the flanged and vented upper section of the pump-tube, the pump-tube-seat being shown in dotted lines.

Fig. 4 is a sectional view, along the line 4—4 of Fig. 2, showing how the pump-tube-seat may be made in separate sections capable of being

assembled in the circular opening of the tank-head, viz., by moving the several segments radially outward, as from the broken-line position to the full-line position at the upper-left.

Fig. 5 is a sectional view of a modified form of the upper end of the pump-tube and its connections that secure it to the head of the barrel or container.

Referring to the drawing in detail, in which similar reference numerals refer to similar parts in the several views, the invention is described in detail as follows:

Referring to Figs. 1 and 2, it is seen that the sheet-metal barrel or tank includes a head 6 and a bottom 7, and may be of any appropriate kind and shape. The head has a circular opening 3 therein, while the bottom has a substantially conical depression 9 therein, the said opening 8 and depression 9 being vertically aligned.

A peripherally grooved and internally threaded annulus or pump-tube-seat 10 is fitted in the opening 8 in such relation that the groove 11 thereof contains and snugly embraces the margin of the opening 8, thus forming a leak-proof joint; and spot-welding or other means may be employed to prevent the member 10 from turning in the opening 8.

The pump-tube is preferably formed of two originally separate sections 12 and 13, the former being preferably thick-walled so as to be sufficiently strong when externally, and internally screw-threaded at 14 and 15, the external threads being normally engaged with the internal threads of the member 10, and the threads 15 being normally engaged with the threaded lower end of a hand-pump 16 which may be of any appropriate kind and may be removed and replaced at will, by turning it into or out of the tube-section 12.

The tube-sections 12 and 13 are united at 17 by the interlapped and swaged connection shown, or by other appropriate means.

The tube-section 13 is of thin bendable and compressible material of such quality that it can be formed while cold, and is changed from its original true-cylindrical shape as follows: First, after making the holes 18 and 19, internal annular ridges 20 and 21 are formed (by external pressure) near its upper and lower ends; second, the valve-guard 22 and check-valve 23 are forced into the respective upper and lower ends until they are arrested by the respective ridges 20 and 21; third, the internal ridges 24 and 25 are formed by pressing against the upper end of the valve-guard and lower end of the check-

- valve, so as to hold these respective devices in their seats; and thereafter, the ridge 26 is formed; or the ridge 26 may be formed simultaneously with forming the ridges 24 and 25 and bending the tongues 27 into the inverted cone shape shown; while reserving the swaging at 17 for the last operation in forming the complete unitary combination of pump-tube, check-valve and valve-guard.
- 10 The valve-guard is preferably of the two-piece sheet-metal construction shown, the lower piece having a cylindrical wall that closes the air-holes 18, this wall merging into an annular horizontal partition or flange 29 that surrounds a central opening or port 30; the upper piece being a disc 31 having an imperforate middle part and having ports 32 at its peripheral part. The imperforate part 31 is over the port 30 and is considerably larger than the latter, so 15 that it is impossible to reach the valve with a rod or other instrument through the port 30. If the valve-guard is moved inward or outward from its seat, the air-holes will be uncovered, thereby rendering the pump inoperative and thus 20 defeating the purpose of anyone attempting to refill the tank through the pump-tube. The parts 28 and 31 are securely united with one another by welding or other means, so they cannot be moved independently of one another. 25 It is quite possible and practical to form them of a single blank into a primarily unitary member; or to make parts 28 and 31 primarily integral.

30 The check-valve, as here shown, includes a valve-seat 33, a valve-closure 34 and a valve-spring 35, although other appropriate forms of valve may be used in lieu of this form.

As the pump is operated by its crank, it creates a suction in the pump-tube 13, so that the 40 liquid is drawn into its lower end through the openings 19; the liquid raises the valve-closure, and passes thence upwards through the ports 30 and 32 of the valve-guard, thence out through the pump 16; but the spring 35 assists gravity 45 in holding the valve-closure tight against the valve-seat when there is a tendency for liquid to return or flow down through the check-valve. During the operation of pumping, air must 50 enter the tank to take place of the pumped liquid; but ordinary air-vents would result in leakage or evaporation of the liquid, especially when the tank is laid on its side, in shipment, and rolled from place to place; so the invention includes a novel means of opening and closing 55 the air-vents which are so small that they cannot be used as practical aids in filling or refilling the tank. Such air-vents are shown at 36 and 37, the same being interdependent and cooperative, but only so when they are in open 60 communication with one another, as shown in Fig. 2. In Fig. 3 they are shown out of the inter-communicating relation, and may be so held by means of a screw 38 through the opening 39 of the horizontal flange of the tube-section 12. The hole 39 is sufficiently larger 65 than the shank or screw 38 to permit the pump-tube to be turned (when the screw is loosened) far enough to bring the air-vents from their closed positions (in Fig. 3) to their open or 70 inter-communicating positions (in Fig. 2).

Each member 10 and 12 is provided with an apertured ear 40 to receive and retain the wire of a seal 41, and the apertures of these ears 75 40 are large enough to allow free movement of

the member 12, for opening and closing the air-vents, without affecting the security of the seal, and the latter prevents the pump-tube from being removed without evidence (by the broken seal) that the device has been tampered with, or that the pump-tube may have been removed for refilling the tank through the pump-tube-seat 10.

80 In shipment, the pump-tube is closed by a screw-plug 42 which may have spanner-holes 43 to receive studs of a spanner (not shown) for removing the plug so the pump 16 can be screwed into the tube-section 12. The same spanner may be either adjustable or reversible so as to fit in the spanner-holes 44 of the member 12, for removing the pump-tube, when the seal is broken at the dealer's filling plant, so the tank can be refilled through the opening from which the pump-tube is removed.

85 In Fig. 5, the parts indicated by reference characters 6a, 10a, 12a, 37a and 40a, correspond to the parts 6, 10, 12, 37 and 40, in Figs. 1, 2, 3 and 4. The part 40b is soldered or otherwise united with the container-head 6a and has an opening under that of the part 40a, so a seal 90 can be passed through and secured in these openings, as at 41 of Fig. 2. The closure or plug 42a has a marginal flange 42b that fits over the air-vents 37a to prevent leakage there-through.

95 Because of the conical lower end of the pump-tube, and of the conical depression in the floor 7, the pump-tube is automatically led into the retaining engagement with the bottom 7, so that the latter cooperates or combines with the head 100 6 in holding the pump-tube rigid so that detriment to the head, which might cause leakage at 105 11, is precluded.

110 Although I have described this embodiment of my invention very specifically, I have no intention to limit my patent protection to these precise details of construction, arrangement, or materials, for the invention is susceptible of numerous changes within the scope of the inventive ideas as implied and claimed.

115 What I claim as my invention is:

120 1. In a liquid dispenser, the combination of a closed tank having a head provided with an opening, a pump-tube normally secured in said opening and extending thence to the bottom 125 part of the tank and provided with means for securing a pump thereto, a check-valve secured in said pump-tube in the operative relation for permitting liquid to be pumped therethrough from the tank and preventing the flow of liquid 130 therethrough into the tank, and a valve-guard seated in said pump-tube between said head and said check-valve in an effective relation for preventing an instrument from reaching through said pump-tube to said check-valve for holding 135 the latter open, said pump-tube having an air-hole therein to render the pump ineffective when connected to said pump-tube and when said air-hole is open, said valve-guard being normally seated over said air-hole for closing the latter 140 and for opening the latter in the event that the valve-guard is displaced from its seat over the air-hole.

145 2. The combination defined by claim 1, said tank being provided with an air-vent through its head, said pump-tube being adjustable with relation to said air-vent and effective to close said air-vent by its adjustment.
